UNITED STATES PATENT OFFICE.

BERNARD CARLIN, OF FLORALA, ALABAMA, ASSIGNOR OF ONE-HALF TO BOBBY H. MEADOWS, OF FLORALA, ALABAMA.

BRIDGE RADIUS ROD AND ENGINE BASE.

Application filed September 10, 1921. Serial No. 499,680.

To all whom it may concern:

Be it known that I, BERNARD CARLIN, a citizen of the United States, residing at Florala, in the county of Covington and State of Alabama, have invented new and useful Improvements in Bridge Radius Rods and Engine Bases, of which the following is a specification.

This invention relates to structural elements of automobiles, particularly of Fords, and has for its object the provision of a novel radius rod structure designed to replace the ordinary V-shaped radius rod whereby to take up the thrust upon the axle and hold the same absolutely rigid at all times.

An important object is the provision of an improved engine base which is of peculiar formation whereby to provide a lubricating cup or depression below the fourth cylinder for effecting efficient lubrication of the fourth connecting rod and its bearings, this base being furthermore of such construction that when removed it will permit ready access to the inside of the engine so that removal of the fourth connecting rod may be effected in a very easy manner.

An additional object is the provision of structural elements of this character which will be simple and inexpensive to manufacture, easy to install, highly efficient in use, durable in service and a general improvement in the art.

With the above and other objects in view, the invention consists in the details of construction to be hereinafter more fully described and claimed, and illustrated in the accompanying drawings, in which:

Figure 1 is a bottom plan view showing my devices in position;

Figure 2 is a side elevation;

Figure 3 is a side elevation of the engine base with parts broken away and in section;

Figure 4 is a detail elevation of one of the radius rod securing brackets;

Figure 5 is a side elevation showing one form of radius rod; and

Figures 6 and 7 are side elevations of modified forms of radius rods.

Referring more particularly to the drawings, the letter A designates the side bars of the frame of a Ford automobile, B designates the front axle, C designates the combined crank case and transmission case, D

designates the transverse rock shaft with which is associated the emergency brake lever.

In carrying out my invention I omit the usual V-shaped radius rods and replace them with a pair of separate radius rods 10 which have their forward ends flattened to define ears which are apertured and through which pass the lower ends of the front spring perches, these ends of the rods being disposed against the under side of the axle and being held in place by the nuts E which hold the spring perches. At their rear ends the radius rods are formed with ball heads 11.

In order that these rear ends may be suitably mounted with respect to the frame, I provide a pair of brackets 12 which are secured upon the under sides of the frame bars A and which are formed with holes 13 which serve as bearings for the ends of the transverse rock shaft D. Each bracket 12 has its lower end formed with a substantially semi-spherical socket 14, and associated with the bracket is a cap 15 likewise formed with a substantially semi-spherical recess or socket 80 cooperating with the socket 14 for receiving the ball head 11. The caps 15 are held in position by means of bolts 16 extending downwardly from the bracket through holes in the caps and provided with nuts 17. It is, of course, to be understood that the nuts 17 might be of such type that they may be screwed up tightly against the cap, though it is preferable to provide coiled springs 18 interposed between the end portions of the cap and the nuts, so as to have the effect of an anti-rattler, the spring tension automatically taking up any play which might be caused by wear.

In Figure 5 I have shown a radius rod 95 which is straight throughout its length, whereas in Figure 6 I have shown a radius rod which is double and which is of V-shape to define upper and lower arms 19 and 20 which are disposed above and below the axle B, respectively, when in applied position.

In Figure 7 the construction is substantially the same as in Figure 6, except that in this instance the arms 21 and 22, which correspond to the arms 19 and 20, are bent intermediate their ends, as indicated at 23.

When my radius rods are used, it is, of course, apparent that the socket member commonly provided on the transmission case 110

is unnecessary, and I take advantage of this fact by providing a specially constructed engine base or removable cover plate for the bottom of the crank case. This cover plate is designated by the numeral 24 and is formed with a series of oil pockets 25 which are of course located below the connecting rods, not shown, for the purpose of lubricating the same. Ordinarily there is no such pocket or depression beneath the cylinder member 4, but in the present case I have shown this plate as provided with such a pocket, which insures efficient lubrication of the fourth cylinder and piston at all times. I have also made this cover plate 24 of greater length than the ordinary plate which corresponds, so that when it is removed there will be ample space, permitting access to the crank case so that removal of the fourth connecting rod may be easily effected in case of necessity. It is, of course, to be understood that this cover plate 24 is held in place by the same means as is ordinarily provided. From the foregoing description and a study of the drawings it will be apparent that I have thus provided a highly satisfactory radius rod structure which will brace the front axle and hold it rigid even under the most trying circumstances, so that there will be no play of any kind. It is also to be noted that the cover plate which I have provided is a distinct advantage as it permits the ac-

cess to the inside of the crank case as above described. 35

While I have shown and described the preferred embodiment of the invention, it is of course to be understood that I have reserved the right to make such changes in the form, construction and arrangement of parts as will not depart from the spirit of the invention or the scope of the subjoined claim. 40

Having thus described my invention, I claim: 45

Means for reinforcing the front axle of an automobile comprising a pair of separate radius rods each of V-shape whereby to provide upper and lower arms having their forward ends secured upon the top and bottom of the front axle, respectively, by means of the spring perches of the axle, the rear ends of the rods being formed with ball heads, brackets secured upon the side bars of the frame and formed with bearings for the transverse emergency brake and clutch operating rock shaft, said brackets being further provided with substantially semi-spherical sockets, the rear ends of the rods being formed with ball heads engaged within said sockets, and spring pressed caps associated with the brackets and engaging the ball heads. 50 60

In testimony whereof I affix my signature.

BERNARD CARLIN.
